UNITED STATES PATENT OFFICE.

JOHN WILSON BROWN, JR., OF PHILADELPHIA, PENNSYLVANIA.

AUTOMATIC BORING-MACHINE.

SPECIFICATION forming part of Letters Patent No. 666,486, dated January 22, 1901.

Application filed April 11, 1900. Serial No. 12,479. (No model.)

To all whom it may concern:

Be it known that I, JOHN WILSON BROWN, Jr., a citizen of the United States, residing in Philadelphia, Pennsylvania, have invented 5 certain Improvements in Automatic Cutting or Boring Machines, of which the following is a specification.

My invention relates to certain improvements in machines for automatically boring 10 or cutting irregular objects. In machines of this type the articles to be bored or cut are placed in a hopper and are automatically fed to the machine and chucked therein. The necessary cuts are then made and the article 15 is released and another article is fed from the hopper automatically.

In the accompanying drawings, Figure 1 is a side view of an automatic boring or cutting machine to illustrate my invention. Fig. 2 20 is a section on the line 2 2, Fig. 1. Fig. 3 is an enlarged sectional plan view. Fig. 4 is a section on the line 4 4, Fig. 3. Fig. 5 is a plan view of a portion of Fig. 1, and Fig. 6 is a view of one of the articles bored on this 25 machine.

My invention is applied to one form of an automatic screw-machine, and I have shown in the drawings only those parts of the machine that are directly connected with the 30 invention.

The invention relates to the mechanism for feeding the article to the chuck and the mechanism for making a concentric cut and an eccentric cut in the article while chucked.

35 I have shown in Fig. 6 of the drawings a view of one of the articles which this machine is especially designed to cut, although it will be understood that the articles may be varied without departing from my invention.

40 In order that the machine can be readily understood, I would state that the figure illustrates the barrel of a rotary pump. The portion x of the barrel is concentric, while the portion x' is eccentric. The machine I will 45 proceed to describe bores the concentric portion and then bores the eccentric portion, so that the interior of the barrel is finished by the one machine without rechucking.

50 A is the base of the machine. A' represents the bearings for the chuck-shaft B. On the chuck-shaft is a gear-wheel K, which meshes with gears on a driving

shaft. On the end of the shaft B is the chuck proper, B', which chuck is hollow and is adapted to receive the piece to be cut, as shown in 55 Fig. 4, these chucks being usually made with means for locking the piece to the chuck, so that it must turn with the chuck, and the piece has usually a lug or projection which enters a recess in the chuck, so that each 60 piece will bear the same relation to the chuck and cutting mechanism.

Mounted in front of the chuck is a carriage D, adapted to transverse ways d. On one end of the carriage D is a hopper E, in which the 65 articles are placed one above another, and at the opposite end of the carriage is a slide-rest F. The carriage D is moved across the machine by the ordinary arms D', pivoted at d' to the frame of the machine and actuated 70 by a cam D² on the operating-shaft D³. This operating-shaft is controlled by any suitable mechanism for giving it a rotary motion at a given time. The hopper E consists of a vertical chamber e, open in front, and directly 75 below the chamber is a rest e' for the lowermost article.

b is an ejector operating in the chuck B', in which there is a slot or recess b' for a use described hereinafter. The ejector mechanism 80 is constructed and operated as fully set forth in the application of Brown and Shellenbach, Serial No. 25,674, filed August 2, 1900. Opposite the ejector and on the same level is a plunger g, supported on a turret G, the whole 85 being constructed and automatically operated by any of the well-known methods commonly used in this form of apparatus.

The slide-rest F can move longitudinally on the carriage D, and mounted on ways on said 90 slide-rest F is a tool-slide F', carrying the two cutters f' f', the two adjustable abutments f² f³, and a lip f⁵. The cutters may be of any suitable shape, according to the work to be performed, and are detachably secured to the 95 slide F', as shown in Fig. 3. The head g² of the turret-plunger g' extends between the abutments and the lip f⁵ of the tool-slide F', so that the turret not only moves the tool-slide F' forward, but also returns it, dispensing 100 with a spring.

Resting between a flange d² on the carriage D and a flange f⁶ on the tool-slide F' are two wedges J and I. The wedge J rests against

the flange d^2 and can be adjusted by means of a screw j . The wedge I moves on the wedge J and is forced out by means of a spring i , mounted in a socket in each wedge, as shown 5 in Fig. 3. The wedge I is forced in by a slide H, described hereinafter. As the wedge I is forced in it moves the slide F forward against the pressure of a spring f^4 , which as soon as the slide is relieved forces it against the stop- 10 screw k . This screw is so adjusted as to allow the wedge I to clear the slide, as shown in Fig. 4.

By manipulating the screw k the size of the circular portion x of the article to be cut can 15 be varied, and by manipulating the screw j the size of the eccentric portion can be varied.

The slide H, which actuates the wedge I, is mounted on ways a' on the bearings A' for the spindle B, and secured to or forming part of 20 the gear-wheel K is a cam k' . This cam acts upon the roller h' on the slide H. A spring h^2 tends to keep the roller in contact with the cam, so that as the cam rotates the slide will be moved in and out.

25 The slide H is reciprocated during the operation of the machine, only acting upon the wedge I when its head i is in line with the head h of said slide. When in this position, it will move the wedge forward against the pressure 30 of the spring i' .

The operation of the machine is as follows: The machine is set for cutting a certain article—say, for instance, the pump-barrel shown 35 in Fig. 6. The barrels in the rough are placed one upon another in the hopper. The first movement of the carriage D is to bring the hopper E in line with the chuck. The elements g and b grasp the article and the hopper recedes. Then the article is moved to- 40 ward the chuck, and when the lug x^2 on the article is in line with the recess b' of the chuck the article is forced into the chuck. The turret then recedes and turns until its plunger g' is in line with the chuck, and the carriage D 45 is moved so that the cutter will be in position to cut the concentric inner surface x of the article. The tool is gradually pushed into the article as it cuts by the turret G, its plunger g' pushing against the abutment f^2 . When 50 the cut has been made, the tool-slide F' is re- turned by the head g^2 on the plunger g' en- gaging the lip f^5 . When the tool is clear, the carriage is again moved forward and also given a transverse movement until the cutter 55 f' is in position to cut the eccentric surface of the article. The head of the wedge I is then in line with the head h of the slide H and the abutment f^3 is in line with the plunger g' . As the plunger g' moves forward it forces the 60 cutter f' into the article. At the same time motion is imparted to the wedge I by the re- ciprocating slide H, and this motion is im- parted to the slide F and tool-slide F', and thus the cutter f' moves toward and from the 65 center of the chuck as the article is turned, accurately cutting the eccentric portion. As soon as the cut is made the cutter is with-

drawn and the article is discharged from the chuck by the ejector b .

It will be seen that all that is necessary is 70 to set the machine to the article to be bored, to keep the hopper loaded, and the cutters in good condition and the machine will automatically chuck the articles, cut both their concentric and eccentric surfaces, and dis- 75 charge them when finished.

While I have described my invention as cutting a particular piece, it will be under- 80 stood that it can be set to cut different articles and will cut either the interior surface, as 85 described, or the exterior surface.

I claim as my invention—

1. The combination in a machine for cut- 85 ting concentric and eccentric shapes, of means for holding and rotating the article to be cut, two cutting-tools, a carrier therefor, means for feeding the tool-carrier to cut the concentric portion, and means for imparting a lon- 90 gitudinal and lateral motion to the tool-carrier to cut the eccentric portion, substantially as described.

2. The combination in an automatic lathe, of a chuck, means for rotating the chuck, a slide carrying cutters, a turret, a plunger on said turret constructed to move said slide lon- 95 gitudinally on the lathe and means for simultane- 100 ously giving a transverse motion to the slide while one of said cutters is in action, substantially as described.

3. The combination of a chuck, a slide car- 100 rying two cutters, means for feeding the cut- 105 ters forward to make a cut, with means for moving first one cutter in line to make a cut and then another cutter in line to make an- other cut and means for giving said slide an independent lateral motion while one of the 110 cutters is working, substantially as described.

4. The combination of means for holding 110 and rotating the article to be cut, a cam, a slide actuated by the cam, a transverse slide 115 carrying two cutters, means for forcing first one cutter and then the other cutter against the article to be bored, a wedge acting on the slide, said wedge when moved into position so that the second cutter will act being in line 120 with the slide actuated by the cam, so that the cutter will be given a lateral motion in- dependent of the forward feed, substantially as described.

5. The combination of means for holding 120 and rotating the article to be cut, a carriage transversely movable in respect to the article, said carriage having a hopper and a slide, two cutters carried by the slide, a turret, means for actuating the turret, a wedge carried by the 125 slide, a longitudinal slide on ways on the fixed part of the machine, a cam for actuating said slide so as to move the wedge, and a spring for retracting the wedge, substantially as de- 130 scribed.

6. The combination in means for holding 130 and rotating articles to be cut, a carriage transversely movable in respect to the article, a slide on said carriage, a tool-slide on the

slide, tools carried by the tool-slide, means for moving the tool-slide longitudinally, two wedges between the slide and the carriage, means for adjusting one of said wedges, and 5 means for operating the other wedge during the time the slide is fed forward, substantially as described.

7. The combination with means for holding and rotating the article to be cut, of a transversely-movable carriage, a slide mounted thereon and also movable transversely, a tool-slide movable longitudinally on said slide, tools carried by the tool-slide, means for automatically moving the said tool-slide, means 15 for moving the slide forward and an adjustable stop on the carriage for the slide, substantially as described.

8. The combination of means for holding and rotating the article to be cut, a slide, 20 tools carried thereby, a headed plunger adapted to feed the tools forward, and a flange on the slide engaged by the headed plunger as it recedes, substantially as described.

9. The combination of a chuck for rotating

the article to be cut, a transversely-movable carriage, a hopper on one end of the carriage and a slide on the opposite end, a tool-slide carried by the slide, a tool thereon, means for operating the carriage, means for feeding the tool longitudinally, and means for reciprocating 25 the tool transversely as the chuck revolves, substantially as described.

10. The combination of a chuck for rotating the article to be cut, a transversely-movable carriage, a hopper on one end of the carriage 30 and a slide on the opposite end, a tool-slide carried by the slide, a tool thereon, means for operating the carriage, means for feeding the tool longitudinally, and means for reciprocating the tool transversely at each revolution 35 of the chuck, substantially as set forth.

In testimony whereof I have signed my name to this specification in the presence of two subscribing witnesses.
